SNAP-OUT PACK

Edward Z. Lewis, Evanston, Ill., assignor to General Manifold & Printing Co., a corporation of Pennsylvania

Application October 11, 1937, Serial No. 168,448

15 Claims. (Cl. 282—24)

This invention relates to improvements in printed forms having interleaved carbon sheets or carbon coatings on the back of some of the sheets, and known commercially as "snap-out" 5 packs.

In such forms as heretofore made, the alternate sheets of record paper and carbon paper are fastened together at the top, either by pasting the same together or by wire stitching the same 10 in various ways. Before assembly, or as they are assembled, the record sheets are perforated or heavily grooved or otherwise weakened so that they may easily be torn out at the perforations or intended line of separation. After the typing 15 operation, the pack is grasped at the top and the bottom and the record sheets torn out in a group, leaving the carbons fastened at the top to the stubs, which latter, with the used carbons, are then discarded. With the use of sheets which are 20 greatly weakened by perforations or heavy slots, it is almost impossible to regulate the slots so that said sheets neither fall apart in the process of collating or hold too fast when pulled away from the stitched or binding edge. Furthermore, 25 if there is an uneven pull on the carbon with respect to the binding edge, the carbon wrinkles. Also, with an uneven pull the carbon-coated material rubs off on the adjacent sheet in the form of streaks.

30 The main object of the present invention is to provide a pad in which the carbons may be easily pulled out from the record sheets, leaving no stub. This is accomplished, generally speaking, by providing a pair of small notches or slots 35 in one edge of the pack and applying an adhesive to the walls of these notches instead of to the edge of the pack. The pack is so arranged that the carbons are available at the edge exactly opposite the small notches so that said carbons may be 40 readily grasped and pulled out. This notched or slotted arrangement of the packs I have designated commercially Wee Notch Packs. Such packs have the following advantages.

The carbons are removed without being 45 wrinkled, and they are removed smoothly without mutilating the underlying parts, as for example by causing streaks. Also they are removed with clean edges, leaving no rough edges on the back except perhaps for the small notches. The sheets 50 forming the pack are held most securely with the least possible amount of adhesive material because the latter is applied in the small notches or slots so that it resists pulls both in a longitudinal and a transverse direction. The slots are preferably rectangular with the result that the ad-

hesive is applied to two parallel walls and to the connecting transverse wall, whereby a small amount of adhesive will afford considerable resistance to a sliding movement of the sheets over each other either longitudinally or transversely, 5 as compared to gumming the edges of paper along the entire length of a straight outside edge or wall. With the rectangular slot there is no possibility that some of the individual sheets fail to receive the adhesive when the forms are being 10 made, as would be the case where only the cut, flush edges of a pack are glued. The carbons are pulled at an indicated point where the resistance is more nearly exactly opposite said point than with any other arrangement, the resisting point 15 referring in this case to the two notches collectively which require a uniform distribution of the pull when removing a sheet, and which insure that the carbons will be pulled out flat and straight.

Another object of the invention, therefore, is to provide a pad in which the forms and the carbons are held together at a few points only, with the sheets of one kind arranged to be grasped almost diametrically opposite these points, so 25 that when the carbons are pulled out there will be an even pull, which avoids wrinkling.

Another object is to provide for this result by the use of an adhesive positioned in small notches or slots cut in the edges of the pack, the adhesive 30 being applied to the walls of said notches, whereby the degree of pull required to separate the sheets may be almost anything desired, depending on the amount of adhesive used and the method of application to the walls of the notches.

A further object is to provide a form of this character which can be fit into a typewriter without the risk of some of the sheets folding back on themselves.

40 A further object is to provide an improved pad comprising a number of individual sets of forms of the character described, the sheets of each set and all of the sets being detachably secured to each other at one edge so that the individual sets may readily be separated one from the other for 45 use in a typewriter or elsewhere.

In the accompanying drawings I have shown several embodiments of the invention which will serve to illustrate the several features of the invention:

Fig. 1 is a plan view of a pack;

Fig. 2 is a side view thereof;

Fig. 3 is a bottom view thereof;

Fig. 4 is a perspective view thereof;

Fig. 5 is a perspective view of the various sheets 55

- displaced from each other to illustrate the assembly;
- Fig. 6 is a perspective view of a modified form of pack;
- 5 Fig. 7 is a plan view of a further modified form;
- Fig. 8 is a perspective view of a duplicate type of pack partly unfolded to illustrate the arrangement of the sheets;
- 10 Fig. 9 shows an auxiliary carbon sheet; and Figs. 10-13 show further modifications.
- In all of these various forms, small slots or notches are employed, with an adhesive applied to the walls of said slots or notches.
- 15 In the first form of the invention the outer sheet is preferably double the length of the other sheets and comprises two sections, 10, 10', separated by a line of weakening in the form of a row of indentations or so-called perforations 11,
- 20 as shown in Fig. 5, these sections forming the upper and lower covers for the pack or unit. Between these two covers are alternate sheets of carbon paper and record paper. Fig. 5 shows a simple arrangement in which there are three
- 25 such sheets, the uppermost sheet comprising a sheet of carbon paper 12, a record sheet 13 being beneath it, and a second carbon sheet 14 beneath said record sheet. The two carbon sheets each have a notch 15 at the top, preferably at the
- 30 middle. The top and bottom cover sheets 10, 10', are each notched at the bottom, as at 16, 16, and the intermediate record sheet 13 is also similarly notched at 17. The notches at the bottom are exactly opposite those at the top.
- 35 The sheets are assembled one over the other in substantially perfect registration to form the pack, and when a plurality of similar packs are superimposed, a pile or pad of any desired thickness results, as shown, for example, in Figs. 2, 3
- 40 and 4. The bottom of the pad may have a sheet of cardboard 18 to stiffen the same.
- The pack is then slotted at the bottom by making two saw cuts 19 in the same, one on each side of the thumb notch 16, and fairly close to
- 45 the same. A suitable adhesive such as glue or cement is then applied to the small slots thus formed and hence all the sheets are held together at two localized points. The slots are preferably rectangular, as shown, i. e. they have three sides,
- 50 two of which are parallel. The amount of adhesive on the parallel walls determines the pull necessary to remove the sheet, as with a deeper notch the side walls are longer and hence the lines of adhesion to be torn apart are longer,
- 55 whereas with a shallower notch the side walls are shorter and the sheets more readily detached. The carbons may extend as far down as the lower edges of the record sheets but as shown in Fig. 1 they terminate preferably just slightly short of
- 60 the lower edges, and, therefore, are held less securely than the record sheets. In use the uppermost pack is readily lifted off, as the packs are secured together at the bottom only, whereas they are free to be spread apart at the top, as
- 65 shown in Fig. 2. Said pack is readily torn off as it is held to the pack beneath it only by the glue in the two bottom grooves or slots. Said pack is then inserted in the typewriter and the typing is done in the usual manner.
- 70 Since the upper margins of the carbon sheets are notched at 15, it is apparent that the two types of sheets may readily be separated by grasping the upper middle portion of the pad with one hand and the exposed carbons at the bottom of the pad with the other hand, exactly opposite the
- upper gripping point, the carbons being pulled out smoothly in the right hand and discarded. The upper and lower sections 10, 10' may then be detached from each other by tearing along the line of weakening 11, thus providing three record sheets in this case. The carbon sheets and the record sheets before being pulled apart are held together only by the adhesive in the slots 19. No adhesive is used at the edge of the pack.
- 10 Where only two sheets are to be pulled out as in the form shown in Figs. 1-5 inclusive, the resistance to separation of each sheet may be made relatively greater than where a larger number of sheets are employed. In the case of a large number of carbons, all of which are removed with a single pull, the resistance per sheet is lessened by using a shallower notch, as previously explained, so that the pull required to separate all the sheets at once will not be excessive. In general, the depth of the notches is made inversely proportional to the number of sheets to be detached at a single pull.
- 15 It will be apparent that additional adhesive on the edge of the pack would be objectionable as it would increase the pull necessary to remove the desired sheets and would thus nullify the carefully regulated resistance to separation arising out of the use of a notch of predetermined depth.
- 20 The carbon sheets may have the transfer material applied thereto over the entire surface or the lower margins may be left uncoated, to avoid soiling the fingers. The provision of notches, having walls parallel to the line of pull, as well as transverse thereto, and the adhesive on said walls, prevents any of the inner sheets, either carbon or record sheets, from accidentally coming loose from the outside folded sheet. Furthermore, the fact that the sheets are enclosed within the folded cover and are each secured to the other
- 25 at the bottom prevents the same from blowing or lifting and folding over when being fed into any kind of typing machine.
- 30 The carbon sheets may have the transfer material applied thereto over the entire surface or the lower margins may be left uncoated, to avoid soiling the fingers. The provision of notches, having walls parallel to the line of pull, as well as transverse thereto, and the adhesive on said walls, prevents any of the inner sheets, either carbon or record sheets, from accidentally coming loose from the outside folded sheet. Furthermore, the fact that the sheets are enclosed within the folded cover and are each secured to the other
- 35 at the bottom prevents the same from blowing or lifting and folding over when being fed into any kind of typing machine.
- 40 In the form of pad shown in Fig. 6 the slots 20 are applied near one corner and the carbons are cut off diagonally at 21 adjacent said slots. The record sheets are cut off diagonally at 22, diametrically opposite the corner where the carbons are cut off. The adhesive is applied as before and the packs may be made up into pads
- 45 substantially as before. The carbon sheets are pulled out diagonally from the record sheets, as will be apparent. The pull, as before, is in a line at right angles to the line connecting the wee notches.
- 50 In the form of pack just described, a larger number of sheets are shown than in the previous forms and with this form it is possible to detach one or two sheets at another point at the bottom without disturbing the carbons, making it possible, as for instance in making out a master invoice 23, to leave the carbons intact and secured to the remaining parts. This is desirable, for example, where the packs are handled roughly during the interval before the weights and exact
- 55 quantities actually shipped are known and which are inserted later. It is understood that in all entry order invoices and shipping combinations, certain sheets go to the plant and others to the office.
- 60 Fig. 7 shows another form in which the slots are at the top of the sheets 24, instead of at the bottom as they are in Figs. 1-5. A duplicate arrangement is shown in Fig. 8, in which two packs such as seen in Fig. 7, are joined in the following
- 65 70 75

manner: An outer sheet or cover is formed in four sections, 25, 25', 25² and 25³, the four units being separated by lines of perforations to show that they may be detached. The sheet, as shown in Fig. 8, is folded on the middle line of perforations to form two halves, each half being folded over and containing alternate record sheets and carbon sheets. Thus two sets of forms are provided each of which may consist of the same number or a different number of record sheets and carbon sheets. One end unit in Fig. 8 consists of the upper sheet or cover section 25, a carbon sheet 26 notched at the top, a second sheet 27 notched at the bottom, a carbon sheet 28 notched at the top, and the lower sheet or cover section 25', all five of these sheets being held together by the adhesive in the slots 29. The lower half of the form is the same, in this instance, as the upper half, each consisting of a folded cover, i. e. two cover sections and three enclosed sheets, or a total of five sheets, held together by the adhesive in the slots cut through the edge of the folded sheet, as will be apparent from the drawings. In each case an additional carbon sheet 30 is inserted between the two sets of forms, which sheet may cover only part of the printed material on the sheet beneath it so as not to transfer all of the typing that appears on the other sheets. Such additional carbon sheet in one form is shown in Fig. 9, in which the coated surface is on the under side. The slots 29 at the top of this sheet indicate how the same would be assembled as part of the combination form shown in Fig. 8, being superimposed on top of the printed form 25 in said figure. After typing, the two halves may be separated, leaving the parts of said two halves intact, i. e. with the sheets adhering to each other. One group of sheets, for example, may be retained in the office and the other group sent to the factory, after which the two groups may be further separated before filing, as in the first case described. The notches 29 in the two halves, of course, register exactly with each other when the sheets are fully folded.

With the arrangement described, it is an easy matter to apply an even pull along a line at right angles to the line connecting the wee notches when the carbons are being pulled out, thus avoiding wrinkling of the sheets and mutilation of the carbons or of the adjacent sheets.

In addition to the advantages of the Figs. 7 and 8 forms previously enumerated, there is the further advantage that the carbons and the record sheets, which may be printed forms, are inserted into the folded outer sheet and are held in place thereby. The edge of the fold which contacts whatever feeding apparatus is encountered, as for example in using a typewriter, addressograph, or rotary feed writing machine, will be free from gum or adhesive of any kind as the adhesive used is in the small notches and is, therefore, set back from the feeding edge. The adhesive, it will be noted, holds all of the parts in their intended positions so that none of them become displaced either in handling or feeding the same into a machine. Also, the adhesive holds together the several forms in the form of a pad, the notches being in such position that a typist working on the forms, lifts a set off the top of the pad without fingering over separate parts of each form, as the folded edge is not gummed and the two notches hold the various sets temporarily in registration, as shown in Fig. 2, for example, and with an almost negligible amount of adhesive.

By graduating the sizes of the thumb notches or half moon cuts, or corner cuts, certain parts after typing of the set may conveniently be pulled out, leaving all the rest of the parts intact. In the case of the half moon cuts, for example, the arcs of the circles of the superimposed sheets would be concentrically arranged whereby the sheets could be pulled out in predetermined order by grasping the exposed areas in the natural order in which they appear. This is illustrated in Fig. 10 in which the folded sheet 31 has substantially concentric, arc-shaped cuts, as a result of which the operator may first grasp the exposed area 32 and pull out a sheet which may, for example, be a delivery slip or slips. When the delivery slips are completed on the part first detached, one part is sent back to permit completion of the invoice which is put back in the typewriter and the additional information is typed. Later the carbon or carbons 33 are pulled out and the various remaining sheets separated and distributed.

The same arrangement may be provided, as for example by means of the corner cuts such as shown in Fig. 6. The triangular areas cut off may be of different sizes, whereby one sheet may be pulled out ahead of the others. As shown in Fig. 6, one of the record sheets has its lower left hand corner projecting for this same purpose, although said projecting corner is not needed where the remaining corners are cut off different amounts.

A further development of this feature is shown in Figs. 11, 12 and 13, in which the outer sheet 34 may be folded as before and provided with small slots or notches 35, 36. Transfer material 37 is provided in the form, preferably, of a separate sheet, or of a carbon coating on the back of the top sheet. All the sheets which are intended to be pulled out ahead of the others, such as the delivery slip 38 may have, for example, a thumb notch 39 at the upper edge near the left hand side, and a cut-out portion or clearance 40 near the right hand side of the upper edge. The sheet 41 has two cut-outs 42 and 43 at the top, arranged in reverse order to those shown in Fig. 12. When the top sheet is grasped between the slots 35 and the exposed sheet or sheets are grasped diametrically opposite this point and pulled, the delivery sheet or sheets will be pulled out, as said sheets are not secured to the other sheets except by the adhesive in the slots 35. The clearance 40 prevents any application of the adhesive to the upper right hand part of said sheet. The assembled sheets are shown in dotted lines in the upper part of Fig. 11. If it is desired next to pull out the carbons, the same may be seized at the lower edge, exactly opposite the area between the small slots 36, which area is grasped at the top. The clearance 43, in this case, permits the removal of the carbons without interference at the slots 35, 35.

Suitable directions may be printed on the upper sheet, as shown in Fig. 11 for example, i. e. "Pull first" at one side, and "Pull carbons" at the other side of the upper sheet. Similar instructions may, of course, be printed on the other parts described herein, wherever appropriate.

While the top and bottom sheets in the several forms shown herein are preferably made from a single folded sheet, two separate sheets may be employed instead. One advantage of the folded sheet is that it provides a tapering or wedge-shaped edge which will more readily pass between the feed rollers of a typewriter or other device into which the parts are fed. Such insertion

- may be further facilitated by having some of the inserted sheets terminate a little short of the folded edge, but not enough to avoid contact with the adhesive.
5. I claim:
1. A snap-out pack comprising alternate record sheets and carbon sheets, a slot in one edge of said pack intersecting all of said sheets and an adhesive in said slot only, to hold said carbon sheets lightly to said record sheets, and providing the sole means for holding said record sheets to each other, whereby said sheets may be detached readily from each other.
  2. A snap-out pack comprising alternate record sheets and carbon sheets, a slot in one edge of said pack intersecting all of said sheets, an adhesive in said slot only to detachably hold said carbon sheets to said record sheets, and providing the sole means for holding said record sheets to each other, said carbon sheets being cut at one side to permit the record sheets only to be grasped and said record sheets being cut on the opposite side to permit the carbon sheets only to be grasped, thus separating the two groups of sheets, when pulled in opposite directions.
  3. A snap-out pack as in claim 2, in which said slot is located in the edge opposite the cut out parts of said record sheets.
  4. A snap-out pack comprising alternate record sheets and carbon sheets, the top and bottom record sheets consisting of a single sheet folded over the other sheets, a slot in one edge of said pack intersecting all of said sheets and an adhesive in said slot to detachably hold all of said sheets lightly to each other and without other fastening means.
  5. A snap-out pack comprising alternate record sheets and carbon sheets, cut-out portions on the edges of said pack exactly opposite each other to provide means for separating certain sheets by grasping the same at the area exposed by the cut-out portion of the adjacent sheet, one of said edges being provided with a slot on each side of and adjacent a cut-out portion, said slot intersecting all of said sheets, and containing a small amount of adhesive material comprising the sole means of securing said sheets to each other.
  6. A pack as in claim 5, in which the top and bottom sheets consist of a single folded sheet, with the remaining sheets inserted therein.
  7. A snap-out pack as in claim 5, in which the outside sheet is approximately four times the size of the pack and has its ends folded toward the center forming two sections, each of said folded sections containing additional record sheets interleaved with carbon sheets, each section being folded on itself with an additional carbon between said sections, said sections being slotted at the folded edges thereof and provided with adhesive in said slots.
  8. A snap-out pack comprising two sets of alternate record sheets and carbon sheets, a slot in one edge of said pack intersecting all of said sheets, an adhesive in said slot to detachably hold said carbon sheets to said record sheets, the top and bottom sheets consisting of parts of a longer sheet folded into two panels, each of said panels being folded on itself and containing record sheets and carbon sheets comprising one of said sets.
  9. A pack of the character described, comprising superimposed record sheets and interleaved carbon sheets, each having an edge aligned with the other edges, two small, spaced, rectangular slots in said edges, an adhesive in each slot applied to the three walls thereof, to resist separation of said sheets by sliding them out of the pack
- in a direction parallel to or at right angles to certain of said walls, and an exposed, designated gripping area on the opposite side of said pack from said slots, arranged equidistant from said slots, to insure simultaneous release of said sheets when gripped and pulled from said pack.
10. A snap-out pack comprising alternate record sheets and carbon sheets, cut-out portions on the edges of said pack exactly opposite each other to provide means for separating certain sheets by grasping the same at the area exposed by the cut-out portion of the adjacent sheet, one of said edges being provided with a slot on each side of and adjacent a cut-out portion, said slot intersecting all of said sheets, and containing a small amount of adhesive material, said pack being provided also with a slot on each side of and adjacent another cut-out portion, said slot intersecting all of said sheets and containing a small amount of adhesive material, whereby after the first sheets are removed, additional material may be written on the remaining sheets and the carbons separated from said remaining sheets.
11. A snap-out pack comprising record sheets with carbon sheets interleaved between the same, said sheets having small, spaced slots in one edge thereof and a cut-out portion opposite the same to permit removal of an underlying sheet by a direct pull, and small additional slots in another part of said pack with a cut-out portion opposite the same, adhesive material in all of said slots to hold said sheets lightly in assembled relation, whereby certain sheets may be removed by a direct pull away from said additional slots.
12. A snap-out pack as in claim 11, in which the said sheets to be detached have cut-out portions adjacent the said slots to permit the withdrawal thereof when the other superimposed sheets are gripped at that point and having also a clearance adjacent the other slots to facilitate said withdrawal.
13. A snap-out pack having a superimposed group of record sheets with interleaved carbon sheets, the top and bottom record sheets having two pairs of slots in one edge thereof and having two thumb notches in the opposite edge thereof, each notch being opposite a pair of slots, certain of the other of said record sheets having slots in registration with said first slots and having a thumb notch adjacent one pair of slots and a cut-away portion providing a clearance adjacent the other pair of slots, adhesive material in each of said slots to hold said sheets in detachable relation, and carbon sheets having a cut-away portion or clearance at the upper edge adjacent the first pair of slots and having a thumb notch in said upper edge adjacent the second pair of slots.
14. A snap-out pack comprising a folded cover sheet, alternating carbon sheets and record sheets therein, cut-outs in the top of each carbon sheet, two slots in the folded edges of said cover sheet registering with similar slots in the upper edge of each carbon sheet on opposite sides of the cut-out therein, a cut-out in the bottom of the said record sheets and an adhesive in said slots to hold the exposed edges to each other.
15. A snap-out pack comprising a folded cover sheet, alternating carbon sheets and record sheets enclosed therein with one edge of each in substantial contact with the fold in said cover sheet, the top and bottom enclosed sheets being carbon sheets, cut-outs in the top of each carbon sheet, two rectangular cuts in the folded edges of said cover sheet intersecting the upper margins of all the sheets therein, the cuts in said

BEST AVAILABLE COPY

5

carbon sheets being evenly spaced on opposite sides of the cut-outs therein, a cut-out in the bottom of said record sheets equidistant from the rectangular cuts therein, said cuts being the
5 same size and having their opposite parallel walls coated to the same extent with an adhesive so

that a light predetermined pull will release said carbon sheets from the pack and whereby said record sheets may thereafter be readily detached from each other.

EDWARD Z. LEWIS. 5
